UNITED STATES PATENT OFFICE.

WILLIAM HENRY MORGAN, OF ALLIANCE, OHIO.

RAILROAD CONSTRUCTION.

1,149,393.

Specification of Letters Patent. Patented Aug. 10, 1915.

Application filed August 5, 1914. Serial No. 855,186.

To all whom it may concern:

Be it known that I, WILLIAM H. MORGAN, a citizen of the United States, and resident of Alliance, in the county of Stark and State of Ohio, have invented certain new and useful Improvements in Railroad Construction, and do hereby declare the following to be a full, clear, and exact description of the invention, such as will enable others skilled in the art to which it appertains to make and use the same.

My invention relates to an improvement in railroad construction, and is an improvement on the invention disclosed in my application Serial Number 840,313 filed May 22nd, 1914.

In the present improvement I have disclosed improved means for locking the rails to the chair, the construction being such that the rails and supporting girders for the latter may be removed without disturbing any of the parts on which the rail carrying girders rest.

In the accompanying drawings, Figure 1 is a view in elevation partly in section of my improvement; Fig. 2 is a view in perspective of a tie, its side wings or projections and chairs; Fig. 3 is a view in perspective of one of the rail carrying plates; Fig. 4 is a similar view of one of the locking strips; Fig. 5 is a view similar to Fig. 1 showing the parts insulated and Fig. 6 is a view of one of the insulating bushings.

1 represents a tie, preferably made of old railroad rail and inverted, so that the base flange of the rail constitutes the top flange 2 of the tie, and 3 are a series of wings riveted or otherwise secured to the web of the tie immediately under the top flange of the latter, and bearing against said top flange. The surface area of these wings together with the parts of the top flange that are exposed, afford ample support for the ties and limit the penetration of the lower edge of the tie into the road bed and by increasing the size of the wings, the bearing surface of the ties may be increased as necessity demands. These wings are preferably made of sheet metal, and are provided with flanged sides and ends, forming open box like structures within which the ballast may pack, and which when tamped or filled, will prevent the tie from creeping either longitudinally or laterally. These wings 3 are preferably provided with lips 4 struck up from the top and adapted to be bent over

the top flange 2 of the tie, for locking the wings to the tie, and each is also preferably provided centrally with a strengthening rib formed by depressing the wings transversely at the centers thereof as shown in Fig. 2. The wings 3 are preferably located, two at each end of the tie and preferably at each side of the chairs. Each chair is composed of two sections 7, preferably made of sheet metal pressed or stamped into shape, and each terminating at its upper end in a shoulder 8 and upwardly projecting flange 9, the free upper edge of which latter curves inwardly toward the rail. Each chair section is strengthened and reinforced by the rib or brace 10, stamped or pressed out from the upright, base member, and shoulder 8 of the section, and extends from adjacent the outer edge of the base member to approximately the outer edge of the shoulder 8, and operates to prevent any outward deflection or collapsing of the chair sections under any stresses to which they may be subjected. The base member 11 of each chair section is provided at its side edges with the flanges 12 which are bent around under the top flange 2 of the tie, and lock the parts or sections of the chair to the tie. If the wings 3 be located under the chair sections, the former should be recessed as shown in Fig. 1, to receive the bent flanges thus permitting the wings to rest up solidly against the bent flanges of the chair sections and also against the top flange of the tie.

Resting on the shoulders 8 of the chair are the wearing strips 13, which are held against longitudinal displacement by an integral tongue 14, which passes through a slot in the top flange 9 of its chair section, the tongue being bent or curved into hook shape so as to prevent any movement of the strip toward the girder 15, which is supported on the strips. The girders 15 are preferably old steel rails, placed head down between the sections of the chairs, with their base flanges resting on said wearing strips 13, which as before explained are seated on the shoulders 8 of the chairs.

Any other form of girder will however answer the purpose, but I prefer old rails, not only on account of their cheapness, but also because of the superior metal of which they are made. They are suspended between the chair sections, clear of the ties, and support the rails throughout the length of the latter, except possibly at switches,

and are arranged to break joints with the rails, so that a joint in the rail and a joint in the girder will not come between the same ties.

5 The rails 16 are loosely seated on the girders, with their base flanges in a plane below the upper edges of the top flanges 9 of the chairs, and are prevented from upward displacement by the locking strips 17 shown in 10 Figs. 1 and 4. These locking strips, are made preferably of steel, and are substantially the length of the top flanges 9 of the chair sections, and each is bent, longitudinally upon itself and curved to approximately 15 conform to the curvature of the top flange 9 of the chair section. The locking strips are driven endwise onto the flanges 9, and are held thereon against upward displacement by friction and the curvature of 20 the parts, and when in place, overhang the base flange of the rail and prevent the possibility of vertical displacement of the latter, but without contacting with said rail, so as not to interfere with a free limited 25 vertical movement, or a longitudinal movement of the rail on the girder.

The free inner edges 18—19 of the locking plates are bent inwardly and form side abutments for the rail, and by making their bent 30 edges of different lengths as shown in Fig. 1, it is possible to move the rail toward its companion rail in order to compensate for wear. As an illustration, suppose the rail 35 16 shown in Fig. 1 should be worn on its left hand side; by simply exchanging the locking strips 17 so that those with the longer projecting edges 18 will be at the right side, instead of at the left as shown, the rail will be shifted to the left a distance equal to the 40 difference in length between the edges 18—19. Each locking strip 17 is also preferably provided with a tongue 20 formed by slitting the inner edges 18—19 of the locking strips as shown in Fig. 4. These tongues 45 are bent downwardly and bear against the top of the hook tongue 14, and together with the outer edge of the locking strips 17, which also bear against the top surface of said tongue 14, lock the wearing strips 13 in place. By removing the locking strips the 50 rails and girders are free to be removed, without disturbing the chair or the wearing plates.

With the construction above described, the 55 load is distributed equally on and between a series of ties and never falls wholly on the ties in the vertical plane of the load, and by enlarging the top flanges of the tie so as to support the ties from the top, the rails can 60 be brought much nearer the road bed, without increasing the depth of the ballast, than they can, when the ties are supported on the bottom flanges. Again the construction as a whole is free of external projection which 65 could be knocked off by the wheels in the

event of a derailment, and by changing the size and cross sectional area of the wearing strips, rails of all sizes and weights may be used without disturbing the chairs, ties or ballast.

If it be necessary or desirable to insulate the rail it can be done as shown in Fig. 5 which is identical with Fig. 1, except that a covering 21 of suitable insulating material is placed over the upper edges of the upwardly projecting flange 9 of the chair section, and a facing 22 of insulating material applied to the lower face of the wearing strips 13, on top face of the shoulders 8 or is inserted as a separate member between 75 said parts. The locking strips 17, make contact with the insulation 21, and hence are insulated from the chairs while the insulation between the wearing strips and the chair insulates the girders on which the rail 80 rests.

The slots in the top flange 9 of the chair section are provided with an insulating bushing 23 which insulates the tongues 14 of the wearing plates from the chairs. These 90 bushings may be a part of the insulating strips 22 or separate therefrom, as may be desired.

When the insulation is used I prefer to have the insulating cover 21, bear against 95 the wearing strips 13 and have the lower end of the locking strips terminate slightly above the wearing strips as shown in Fig. 5.

It is evident that many slight changes might be resorted to in the relative arrangement of parts shown and described without departing from the spirit and scope of my invention. Hence I would have it understood that I do not wish to confine myself to the exact construction and arrangement of 105 parts shown and described but

Having fully described my invention what I claim as new and desire to secure by Letters-Patent, is:—

1. In a railroad track construction, the 110 combination of a tie, a chair having a shoulder and a top flange, a wearing strip on the shoulder and a rail locking device engaging both faces of said top flange above the wearing strip and adapted to overhang the 115 base flange of the rail.

2. In railroad track construction, the combination of ties, chairs secured to the latter and having supporting shoulders and a top flange, and rail locking strips engaging both 120 faces of said top flange and adapted to overhang the base flange of the rail.

3. In railroad track construction, the combination of a tie, a chair having a curved top flange and a rail locking strip secured 125 to and engaging both faces of said curved top flange and overhanging the base flange of the rail.

4. In railroad track construction, the combination of a tie, a chair having a curved 130

top flange and a rail locking strip bent upon itself and curved to conform to the curvature of the top flange and engaging both faces of the latter.

5. In railroad track construction the combination of a tie, a chair having a shoulder and a top flange, a wearing strip resting on said shoulder and a locking strip engaging both faces of said top flange and bearing at 10 its free edges against the wearing strip.

6. In a railroad track construction, the combination of a tie, a chair having a shoulder and a top flange, a wearing strip on said shoulder and provided with a tongue 15 passing through a slot in the flange and a locking strip bent to engage both faces of the top flange and curved to overhang the base flange of the rail, the free edges of said locking strip engaging the wearing strip.

20 7. In railroad track construction, the combination of a tie, a chair having a shoulder and a top flange and a rail locking strip embracing and bearing against both faces of said top flange and overhanging the base 25 flange of the rail, the inner edges of said strip forming side abutments for the flange of the rail.

8. In railroad track construction, the combination of a tie, a chair having shoulders 30 and top flanges, and rail locking strips embracing and bearing against both faces of said top flanges and overhanging the base flange of the rail, the inner edges of said locking strips being of unequal lengths and 35 forming side abutments for the rail.

9. In railroad track construction the combination of a tie, two part chairs thereon, each part of a chair having a shoulder and a top flange, girders suspended from said 40 shoulders, rails resting on the girders and locking strips each embracing both faces of the top flange of a chair section and overhanging the base flange of a rail.

10. In railroad track construction, the 45 combination of a tie, two part chairs thereon, each part of a chair having a shoulder

and a top flange, wearing strips on said shoulders, girders supported on said wearing strips, rails resting on the girders, and locking strips each embracing both faces of 50 the top flange of a chair section and overhanging the base flange of a rail.

11. In railroad track construction, the combination of a tie, a chair having a top flange and a rail locking strip bent upon 55 itself and conforming to the shape of the top flange and engaging both faces of the latter.

12. In railroad track construction, the combination of a tie, a chair having a top 60 flange, a rail locking strip bent upon itself and conforming to the shape of said top flange and engaging both faces of the latter, insulating material between said top flange and rail locking strip and insulating mate- 65 rial between the rail and the chair.

13. In railroad track construction, the combination of a tie, a chair having a curved top flange, a rail locking strip bent upon itself and conforming to the shape of 70 said top flange and engaging both faces of the latter, insulating material covering that portion of the top flange embraced by the locking strip and insulating material between the rail and chair. 75

14. In railroad track construction, the combination of a tie, a chair having a shoulder and a curved top flange, insulating material covering the upper end of said top flange, rail locking means secured against 80 said covering and overhanging but not contacting with the base flange of the rail, a wearing strip on the shoulder of the chair and insulating material between said shoulder and wearing strip. 85

In testimony whereof, I have signed this specification in the presence of two subscribing witnesses.

WILLIAM HENRY MORGAN.
